(Cl. D71—1)

To all whom it may concern:

Be it known that I, Robert L. Kamery, a citizen of the United States, residing at Tucson, in the county of Pima and State of Arizona, have invented a new, original, and ornamental Design for an Autogyro, of which the following is a specification, reference being had to the accompanying drawings, forming part thereof.

Figure 1 is a top plan view of an autogyro showing my new design,

Figure 2 is a side elevational view,
Figure 3 is a front elevational view, and
Figure 4 is a rear elevational view.

I claim:

The ornamental design for an autogyro, as shown.

ROBERT L. KAMERY.
